To all whom it may concern:

Be it known that I, Neil S. Waterman, a citizen of the United States and a resident of Stamford, county of Fairfield, State of Connecticut, have invented a new, original, and ornamental Design for a Cigar Package or the like, of which the following is a specification, reference being had to the accompanying drawing, forming a part thereof.

On the drawing:

Figure 1 is a perspective view of a cigar package or the like embodying my new design;

Figure 2 is a top plan view thereof;

Figure 3 is a front elevational view thereof; and

Figure 4 is an end elevational view thereof.

The sides of the package not shown are the same as those shown.

I claim:

The ornamental design for a cigar package or the like, substantially as shown and described.
